J. B. PAGE

ROAD OR PAVEMENT

Filed May 24, 1920

Inventor
James Benton Page,

By *K. P. Dr. Elroy*
- his Attorney

UNITED STATES PATENT OFFICE.

JAMES BENTON PAGE, OF BIRMINGHAM, ALABAMA.

ROAD OR PAVEMENT.

Application filed May 24, 1920. Serial No. 383,739.

To all whom it may concern:

Be it known that I, JAMES BENTON PAGE, a citizen of the United States, residing at Birmingham, in the county of Jefferson 5 and State of Alabama, have invented, certain new and useful Improvements in Roads or Pavements, of which the following is a specification.

This invention relates to roads or pavements; and it comprises a road or pavement having a base of flat hollow tile laid horizontally and vertical hollow tile arranged thereon with a filling of relatively coarse material in the vertical hollow tile, advantageously to a point slightly below their upper ends, and a finishing surface of asphalt, macadam or the like as a top, extending within the vertical tile; all as more fully hereinafter set forth and as claimed.

20. An object of my invention is the provision of a road in which the base or concrete is strongly reinforced and in which the top or the surface is held in position by the reinforcing means.

25. In the accompanying drawings I have shown one form of a specific embodiment of my invention. In the drawings;

Figure 1 is a transverse section through a road built in accordance with my invention;

Figure 2 is a top view partly in section (the section being taken at different points) along line 2—2 of Figure 1;

Figure 3 is a detailed perspective of one form of vertical hollow tile I may employ; and

Figure 4 is a similar view of the flat hollow tile.

The hollow flat tiles 1 are laid face down 40 in the bottom of a proper excavation, and the vertical tiles 2 are placed thereon preferably in such a position that the lower end of the tiles 2 crosses meeting ends of the flat tiles 1. The material which is to constitute the base of the road is thereupon placed in the vertical tiles and rests upon the face of the tiles 1, some of it passing be-

tween adjacent tiles 1. Advantageously the base material which I have indicated as 3 may consist of concrete or the like and is 50 used to fill the vertical tiles to a height somewhat short of their upper ends. The "top" 4 which may consist of asphalt or macadam or the like is then placed upon the tile base, and is rolled and tamped into position corresponding to the contour of the foundation so that the road may have a crown, as shown, extending to curbing or gutters 5 and 6. The asphalt or macadam forms a continuous smooth surface. The vertical 60 tiles act as reinforcement for the road, both transversely and longitudinally. In warm weather if there is any tendency of the asphalt road surface to flow this is overcome by the reinforcing effect of the vertical 65 tiles. The construction outlined results in a number of shoulders extending upwardly into the asphalt when it is rolled into the vertical or upstanding tiles. This will stop the flow or movement, swelling or buckling 70 of the asphalt when it is rolled or tamped into position.

The serrated surfaces of the tile receive the base material with the result that the tiles are locked to each other and the base 75 material is securely held in position.

What I claim is:—

1. A road comprising two layers of hollow tiles the lower layer being arranged flatwise and the upper layer being arranged vertically thereon, with a filling of base material in the vertical tiles and a top of finishing material on the base material.

2. A road comprising two layers of hollow tiles, the lower layer being arranged flatwise 85 and the upper layer being arranged vertically thereon, with a filling of base material in the vertical tiles to a point below the top thereof, and a filling of the finishing material or top on said base extending downwardly into the vertical tiles.

In testimony whereof, I affix my signature hereto.

JAMES BENTON PAGE.
